HYDRAULIC JACK

Ira Morgan White, Walnut Creek, Calif., assignor
to The Pelton Water Wheel Company, San
Francisco, Calif., a corporation of California

Application August 5, 1946, Serial No. 688,498

8 Claims. (Cl. 60—51)

1

My invention relates to means especially designed for use in connection with deep well reciprocating pumps for the purpose of operating the pump rod to discharge pumped fluid from the well. Devices of this nature have come into use in deep petroleum wells in which it is necessary to supply a pumping structure of considerable capacity capable of operating at relatively high pressures. There is customarily employed a pumping jack including a cylinder having a reciprocating piston therein. The cylinder is periodically supplied with hydraulic fluid, such as oil, from a storage tank through the medium of an actuating pump and is alternately deprived of oil by the pump, the oil being returned to the storage tank. To secure a partial balance of the reciprocating parts the storage tank customarily is closed and is provided with an air cushion operating at a suitable pressure so that the load on the oil pump is approximately constant. It has been found in practice that the air cushion tends to become depleted due to loss of air from various causes.

It is therefore an object of my invention to provide in a hydraulic jack mechanism a means for maintaining a suitable body of air in the balancing tank.

It is another object of my invention to provide a hydraulic jack in which the pressure air supply is automatic.

A further object of the invention is to provide a hydraulic jack in which the air supply can readily be adapted to mechanism already available in the hydraulic jack assembly.

A further object of the invention is to provide in a hydraulic jack an air supplying structure capable of regulating the supplied air pressure.

An additional object of the invention is to provide a hydraulic jack of a generally improved character.

Other objects together with the foregoing are attained in the embodiment of the invention disclosed in the accompanying drawing, in which the figure is a diagrammatic disclosure of the hydraulic jack of my invention, incorporating the air supplying means therein.

While the hydraulic jack of my invention is susceptible to utilization in a number of different environments and is capable of variation depending upon various operating characteristics, it has successfully been embodied as shown in the accompanying diagram. Some of the structures diagrammed are more fully illustrated in the patent of Fred H. Rued, 2,481,623, issued September 13, 1949, and entitled Pumping Jack. The

mechanism includes a main jack cylinder 6 usually installed vertically over a well to be pumped and serving as a housing for a reciprocable piston 7, secured to the end of a rod 8 connected to the sucker rod of a deep well pump. A suitable amount of oil under appropriate pressure is supplied to or withdrawn from the cylinder 6 beneath the piston 7 through a lower port 9 and a connecting conduit 11 extending to a port 12 in a main valve, generally designated 13. The main valve 13 is primarily a cylindrical housing having a number of different ports and passages therein and containing a valve shuttle 14. Incorporated in the valve shuttle is a central spindle 16 and a valve head 17, in one position of the valve disposed to one side of the port 12, and a similar valve head 18 in that position of the valve disposed on the other side of the port 12. A head 19 comparable to the head 17 is in this position 20 of the valve disposed adjacent one end of the valve housing.

The arrangement of the port 12 with respect to the heads 17 and 18 and also with respect to an inlet port 21 is such that, in the illustrated position of the valve, oil from a suitably driven main pump 22 is discharged into the cylinder 6. The oil is received by the pump 22 from a balancing tank 23 through a conduit 24 and through ports 26 and 27 disposed in this position of the valve 30 between the heads 18 and 19 and through a conduit 28 to a pump inlet pipe 29. Thus oil from the balancing tank 23 is drawn by the pump 22 through the control valve 13 and is then forced again through the control valve into the jack cylinder 6, so that during the operation of the pump under these circumstances oil under pressure is supplied beneath the piston 7 and the rod 8 is lifted.

The lifting action of the piston 7 continues 40 until the piston has overridden a selected one of a plurality of ports 31, 32, 33 and 34 in the cylinder 6. The effective one 33 of such ports is connected through a rotary selector valve 36 and through a check valve 37, affording flow in the direction 45 of the arrow, to a conduit 38, extending to a pilot valve.

The pilot valve is primarily a body 39 having a cylindrical bore within which operates a shuttle 41 having a central stem 42 at one end of which 50 a head 43 is disposed. Pressure from the conduit 38 acts through a port 44 upon the head 43 and tends to translate the shuttle 41 to the right in the figure. This pressure is in part opposed by pressure upon a head 46 at the end of the stem 42. 55 The head 46 slides within a chamber 47 forming

an extension of the valve body 39 and connected by a conduit 48 to the interior of the balancing tank 23. The body 49 of oil in the tank is effective to transmit the interior tank pressure through the conduit 48 against the head 46 to oppose the pressure upon the head 43. Leakage past the head 46 discharges through a port 51 into a conduit 52 leading to a sump 53 open to atmospheric pressure. Leakage past the head 43 discharges through a port 54 into a line 56 likewise leading to the sump 53. Due to the fact that the diameter of the head 43 is much greater than that of the head 46, whereas the unit pressure acting against both heads is approximately the same, there is a resultant unbalanced pressure effective under the described conditions to move the shuttle 41 to the right, as seen in the figure. When such motion is accomplished, the shuttle 41 is shifted so that the head 46, the head 43, and an intermediate head 57 are all moved to the opposite extreme position. The head 57 then lies on the right side of a pressure line 58 extending to the valve body 39 from a scavenging pump 59 suitably operated from a motor (not shown).

The scavenging pump withdraws hydraulic fluid from the sump 53 through an intake duct 61. From the discharge conduit 58 a by-pass line 62 leads to a relief valve 63 closed normally by a spring 64. The valve 63 is opened by a pressure in excess of a predetermined pressure to permit flow from the conduit 62 through the valve 63 and through a return conduit 66 to the sump 53. With this arrangement when the pressure is excessive the scavenging pump 59 is effective merely to circulate the excess pressure oil locally from the sump through the pump but when the pressure is less than a predetermined amount the scavenging pump discharges only through the line 56 into the interior of the pilot valve body 39 through a port 67. When the head 57 is on the right hand side of such port the pressure fluid then flows from the pilot valve body 39 through a discharge port 68 into a conduit 69 leading to a port 71 in one end of the body of the main valve 13. Thus the end of the head 49 is exposed to the scavenging pump pressure. The main valve shuttle 14 is substantially unbalanced as its opposite head 17 is provided with a discharge port 72 leading through a conduit 73 back to a port 74 in the pilot valve body 39.

When the pilot valve shuttle is in a position opposite to that shown, flow from the conduit 73 is then through the body 39 from a port 76 therein and through a short line 77 into the discharge conduit 52 leading back to the sump 53. Because of the unbalanced pressure existing on the main valve shuttle 14 it is translated from the position shown in the figure to a position in the other extreme end of the valve body. Thus, when the piston 7 overruns the port 33 there is produced a translation of the shuttle 41 which in turn produces a corresponding translation of the main valve shuttle 14. When this occurs the head 18 changes sides and occupies the left side of the pump discharge port 21. Flow is then from the main pump 22 through the outlet port 26 and the line 24 back into the pressure tank 49. Simultaneously the conduit 11 is connected through the port 12 and an outlet port 78 in the body of the main valve 13 so that oil flows from the cylinder 6 through the main valve body and port 78 and through a conduit 79 to the pump inlet conduit 29 for return to the balancing tank 49.

As the piston 7 descends, the space above it is substantially at atmospheric pressure. This con-

dition persists until the piston 7 has lowered sufficiently to uncover a control line 81 having a suitable check 82 therein and communicating with the line 38. When the line 38 is thus exposed to atmospheric pressure, flow to relieve the pressure in the line 38 takes place through the check 82. The pressure exerted on the head 43 is thus dropped approximately to atmospheric. The pressure on the smaller head 46 is still considerably above atmospheric, as the head is exposed through the connection 48 with the balancing tank pressure. The unbalanced pressure shifts the pilot shuttle 41 back into the position shown in the figure. Consequently flow from the scavenging pump 59 goes through the port 67 and through the pilot valve body 39 to discharge from the port 74 through the line 73 into the body of the main valve 13. The head 17 is thus exposed to the scavenging pump pressure while at the same time the pressure on the opposite head 19 of the main valve is reduced approximately to atmospheric. This is because pressure communication is through the port 71 and the line 69 and the ports 68 and 54 in the pilot valve with the discharge line 56 leading to the sump 53. The described cycle is repeated indefinitely under control by the motion of the piston 7 within the cylinder 6 in turn affecting the motion of the shuttle 41. This in turn affects the operation of the main valve 13, itself controlling the supply of oil from the balancing tank 49 to the cylinder 6 and the return of oil from the cylinder to the balancing tank.

During operation it is one of the functions of the scavenging pump 59 to return excess oil to the balancing tank 23 and to maintain a suitable level of oil for operation within the sump 53. For this reason substantially all of the leakage or drainage oil is led back to the sump 53 but that may not be sufficient to provide adequate oil for the sump. A make-up means is provided. When the pilot shuttle 41 is translated to the opposite position from that illustrated in the figure, the scavenging pump discharges through its conduit 58 and the port 67 and then through the port 68 and the conduit 69 into the body of the main valve 13. If the main valve is displaced from the position shown in the figure, oil flows from the port 71 through the end chamber of the body to an outlet port 83 leading into a line 84. This line leads to a valve 86 controlled by a float 87 responsive to the level of oil in the sump 53 and governing flow through a pipe 88 into the sump. If the sump level is low the scavenging pump is effective locally to circulate oil and to pump it back into the sump 53. When there has been sufficient leakage and the sump level is correspondingly high, the valve 86 is closed and fluid in the conduit 84 then flows through a branch pipe 89 leading through a check 91 into the balancing tank 23 which also serves as a reservoir.

In accordance with my invention the fluid discharged by the scavenging pump is utilized to actuate a means for supplying make up air to the balancing tank 23. When the pilot valve is in the position shown in the figure, the scavenging pump discharges through the aperture 74 and through the duct 73 and the port 72 into the end chamber in the main valve. Additionally the line 73 might discharge through an extension 92 except for a check 93 which opens only in the opposite direction. When the main valve occupies the position shown in the figure, flow through the aperture 72 into the valve body has a choice of

two paths. It can proceed through a port 94 connected by a conduit 96 to a valve 97. This valve is normally closed by a spring 98 yet is opened upon the occurrence of an excessive pressure or one higher than a predetermined pressure to permit the passage of oil through the valve and through a duct 99 back into the sump 53. The pressure at which the valve 97 opens is less than that at which the relief 63 opens. If therefore the pressure of the oil in the line 73 or its connections is excessive when the main valve is translated as shown, the excess oil can travel through the conduit 96 and by opening the valve 97 can escape to atmospheric pressure through the conduit 99 into the sump 53. When the pressure is below a set or predetermined value, this avenue of egress is closed by the valve 97 and only the alternative path can be utilized. The amount of flow through the alternative path is small and is more in the nature of a pulse.

The alternative path includes a port 101 leading from the main valve body 13 through a conduit 102 merging with a pipe 103 adjacent the check valve 93. The conduit 103 extends to an air compressor 104. The structure of this air compressor can be varied to suit individual circumstances, but in the present instance it comprises a main cylinder body 106 within which is disposed a reciprocable plunger 107 having an enlarged piston 108 thereon exposed to the pressure of oil entering through the conduit 103. Likewise included in the plunger is a reduced diameter portion 109 designed to reciprocate within a reduced cylinder 111. Between the enlarged and the reduced cylinder portions there is formed a variable chamber 112, connected by a pipe 113 to the air space 114 within the balancing tank 23. When the pressure within the chamber 106 is in excess of the resultant pressure on the other side of the head 108, plus the pressure on the plunger 109, the plunger is translated upwardly as seen in the figure. When the pressure within the chamber 106 is low, tank pressure within the chamber 112 is effective to translate the plunger downwardly as seen in the figure. The extension 109 serves as an air pump. In its lowermost position it uncovers an air port 116 communicating through a duct 117 and a check valve 118 to the atmosphere. The cylinder 111 is provided with a check valve 119 controlling flow from the cylinder through a duct 121 into the air space 114.

Fluid under pressure from the scavenge pump 59 flows through the pipe 73 and the pipe 102 into the conduit 103 and lifts the plunger piston 108. The rising piston cuts off the port 116 thus trapping a body of air and during its further motion compresses the trapped air sufficiently to unseat the outlet check 119 and to displace the air into the chamber 114. This position of the plunger is maintained until such time as the main valve shuttle 14 is translated to the opposite extreme position from that shown in the figure and has cut off the port 101. The shift of the shuttle 14 is caused by a shift of the pilot valve shuttle 41 connecting the port 74 with the port 76. Since the latter is connected by the conduit 52 to the atmospheric pressure sump 63, the pressure within the conduit 73 likewise drops substantially to atmospheric. Under these circumstances the intermediate pressure from the chamber 114 is exerted to close the check valve 119 and is effective upon the differential area between the head 108 and the portion 109 to force the plunger 107 downwardly. This motion discharges the oil previously contained in the cylinder 106 through the con-

duit 103 and past the check valve 93 into the connecting pipe 92 and so into the conduit 73 and finally back to the sump. Having returned to its lowermost position, the air pump plunger 107 deriving its power from the scavenge pump 53 is set for a repetition of the cycle of operation in response to the operation of the main valve 13 and of the pilot valve. The pressure of the air in the chamber 114 is regulated by the pressure at which the valve 97 is forced open by the actuating liquid.

I have thus provided in accordance with my invention in a hydraulic jack system including a main cylinder, a balancing tank, a main valve 15 and a scavenge pump, a means for supplying make up air to the balancing tank, the make up air supply means being governed and actuated by the scavenge fluid and the pressure of the air being regulated in accordance with any set or desired value. The structure of the air pump is a type which can be readily incorporated with previously existing hydraulic jacks since it relies upon a hydraulic drive readily provided by the installation of appropriate conduits and pipes. 20 There is afforded by my invention an improved air supply for a hydraulic pumping jack mechanism.

I claim:

1. In a hydraulic jack having a balancing tank 30 for containing air and oil, a main pump, a control valve for governing oil flow to and from said tank through said main pump, and a scavenge pump for periodically discharging oil into said tank under control of said valve, the combination of an air compressor cylinder communicating with the atmosphere and with said tank, check valves for said cylinder, a plunger in said cylinder, and means responsive to the operation of said control valve for alternately subjecting 35 an actuating surface of said plunger to the pressure of oil discharged by said scavenge pump and to atmospheric pressure.

2. In a hydraulic jack having a balancing tank for containing air and oil, a main pump, a control valve for governing oil flow to and from said 45 tank through said main pump, and a scavenge pump for discharging oil into said tank under control of said valve, the combination of an air compressor communicating with the atmosphere and with said tank, means for utilizing oil discharged from said scavenge pump to drive said compressor, and means responsive to the operation of said control valve for controlling said utilizing means.

3. In a hydraulic jack having a balancing tank for containing air and oil, a main pump, a control valve for governing oil flow to and from said tank through said main pump, and a scavenge pump for discharging oil into said tank under 50 control of said valve, the combination of an air compressor discharging into said tank, means including said scavenge pump for driving said air compressor, and means responsive to the operation of said control valve for controlling said driving means.

4. In a hydraulic jack having a balancing tank for containing air and oil, a main pump, a main control valve for governing oil flow to and from said tank through said main pump, and a pilot valve for operating said main valve, the combination of an air compressor discharging into said tank, a secondary pump for driving said air compressor, and means responsive to the operation of said pilot valve for controlling the driving of 55 said compressor by said secondary pump.

5. In a hydraulic jack having a balancing tank for containing air and oil, a control valve for governing oil flow to and from said tank, and a scavenge pump for discharging oil into said tank under control of said valve, the combination of an air compressor for supplying air to said tank, means for utilizing oil discharged from said scavenge pump to drive said compressor, means responsive to the operation of said control valve for controlling said utilizing means, and means responsive to the pressure of oil discharged from said scavenge pump in excess of a predetermined value for rendering said supplying means inoperative.

6. In a hydraulic jack having a balancing tank for containing air and oil, an atmospheric pressure tank, and a scavenge pump for discharging oil from said atmospheric pressure tank into said balancing tank, the combination of an air compressor for supplying air to said balancing tank, means for utilizing oil discharged from said scavenge pump to drive said compressor, and means responsive to the pressure of said discharged oil in excess of a predetermined value for rendering said supplying means inoperative.

7. In a hydraulic jack having a cylinder with a port therein, a piston reciprocable in said cylinder to cover and uncover said port, a balancing tank for containing air and oil, a main pump, a control valve connected to said port for governing oil flow to and from said cylinder and to and from said tank through said main pump, and a scavenge pump for discharging oil into said tank

under control of said valve, the combination of an air compressor discharging into said tank, means including said scavenge pump for driving said air compressor, and means responsive to the operation of said control valve for controlling said driving means.

8. In a hydraulic jack having a cylinder with a port therein, a piston reciprocable in said cylinder to cover and uncover said port, a balancing tank for containing air and oil, a main pump, a main control valve for governing oil flow to and from said cylinder and to and from said tank through said main pump, and a pilot valve connected to said port for operating said main valve, the combination of an air compressor discharging into said tank, a secondary pump for driving said air compressor, and means responsive to the operation of said pilot valve for controlling the driving of said compressor by said secondary pump.
